UNITED STATES PATENT OFFICE.

ARTHUR T. GOLDSBOROUGH, OF SAN FRANCISCO, CALIFORNIA.

GARMENT.

Application filed December 7, 1921. Serial No. 520,596.

To all whom it may concern:

Be it known that I, ARTHUR T. GOLDSBOROUGH, a citizen of the United States, residing in the city of San Francisco, in the county of San Francisco and State of California, have invented certain new and useful Improvements in Garments, of which the following is a specification.

My invention consists in a new and useful improvement in garments, and is designed to provide a body garment which, while serving as a back protector, affords suspension means for the wearer's nether garments, and also provides an effective belt for confining the waist-bands of such garments.

A particularly valuable feature of my improved garment is the ease and simplicity of its investiture, since it is provided with six button holes by which it may be buttoned upon the six suspender buttons ordinarily provided upon bifurcated nether garments. While I have provided the usual means of adjusting the suspension means and the belt to accommodate the garment to wearers of different sizes, when the parts are adjusted the garment may be put on and taken off by merely the manipulation of the buttons ordinarily used for suspenders without having to resort to the use of any buckles or other fastening means.

I have indicated in the drawings filed herewith one specific embodiment of my invention, but it is to be clearly understood that I do not consider my invention limited to the details of construction illustrated, but refer for its scope to the claims appended hereto.

In the drawings:

Fig. 1 is a front view of my device.

Fig. 2 is a rear view.

Fig. 3 is a horizontal sectional view on the line 3—3 of Fig. 1.

Fig. 4 is a vertical sectional view on the line 4—4 of Fig. 3.

In the drawings:

My improved garment comprises a back portion A provided with a pair of elastic shoulder straps B, B. The portion A has at its lower edge a hem A¹ and is provided with a pair of button holes A², A², so disposed as to be adapted to receive therethrough the two ordinary suspender buttons P¹, P¹, upon the rear of the pants P of the wearer of the garment. The shoulder straps B, B, are provided at their ends with thongs, B¹, B¹, which may be adjustably and re-

movably fastened to the straps B, B, respectively, in the well known method obtaining in suspenders. Each of these thongs B¹ is provided with a button hole, B². These thongs, B¹, B¹, are adapted to be buttoned upon the two ordinary suspender buttons, P², P², at the front of the pants P. The back A is so shaped that the ends A³, A³, of the hem A¹ extend to the sides of the wearer. Each of these ends A³, A³, is provided with a buckle, A⁴, in which may be fastened an elastic strap, C, which carries in its outer end a thong C¹, provided with a button hole C². The inner end, C³, of the strap C is received within the hem A¹. The thongs C¹, C¹, may be buttoned upon the ordinary suspender buttons P³, P³, of the pants P adjacent the buttons P², P².

From the foregoing description of the parts of my garment it will be obvious that I provide a covering for the back of the wearer, suspenders to support the pants, and a belt to retain the proper shape of the upper part of the pants.

Having described my invention, what I claim is:

1. In a body garment, the combination of a back covering provided with two button holes; a pair of suspender straps attached to the upper edge of said covering and each provided in its end with a button hole; and a pair of belt straps, each attached to one side of said covering and provided with a button hole.

2. The combination in a garment of a back member provided with a hem; two buckles each attached at one end of said hem; an elastic strap adjustably carried in each buckle and having one of its ends confined in said hem; and a strap provided with a button hole attached to the free end of each strap.

3. The combination in a garment of a back member provided at its bottom with a hem; two buckles each attached at one end of said hem; an elastic strap adjustably carried in each buckle and having one of its ends confined in said hem; a strap provided with a button hole attached to the free end of each strap; two elastic straps attached to the top of said back member; and a strap provided with a button hole adjustably attached to each of said top straps.

In testimony whereof I affix my signature.

ARTHUR T. GOLDSBOROUGH.
